CLAIM

The ornamental design for a scratching and self-grooming tool, as shown and described.

DESCRIPTION

FIG. 1 is a perspective view of a scratching and self-grooming tool showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.

1 Claim, 4 Drawing Sheets
